UNITED STATES PATENT OFFICE.

CHARLES W. HASELTON AND GRANVILLE P. FELT, OF PETERBOROUGH, N. H.

SEAM-PRESSING MACHINE.

SPECIFICATION forming part of Letters Patent No. 357,432, dated February 8, 1887.

Application filed June 15, 1886. Serial No. 205,269. (No model.)

To all whom it may concern:

Be it known that we, CHARLES W. HASELTON and GRANVILLE P. FELT, of Peterborough, in the county of Hillsborough and State 5 of New Hampshire, have invented certain new and useful Improvements in Seam-Pressing Machines, of which the following is a specification.

Our invention relates to seam pressing or "rubbing" machines employed in the manufacture of boots and shoes, and has for its object to provide a contrivance of that character which shall be simple in construction and convenient in use, and by which the seam 10 may be guided with exactness and certainty to the proper point on the pressing or rubbing devices, and be thoroughly and smoothly pressed down or flattened in the desired manner.

20 To these ends our invention consists in the improvements which we will now proceed to describe, so that those skilled in the art may be able to make and use the same, the invention being particularly set forth in the claims 25 appended to the description.

Of the drawings hereto annexed and forming a part of this specification, Figure 1 represents a front view of the machine constituting our invention. Fig. 2 represents an end 30 view thereof. Fig. 3 represents a section on the line *x* *x* of Fig. 1. Fig. 4 represents a section on the line *y* *y* of Fig. 2. Figs. 5 and 6 are diagrammatic views designed to represent the seam in the process of and after being operated upon.

Similar letters of reference indicate similar parts in all of the figures.

a represents the bed of the machine, having a post or standard, *b*, secured thereto or formed 40 integral therewith, from the upper end of which projects an arm, *c*, supporting a shaft, *d*, so that the latter may be revolved therein.

To one end of shaft *d* the driving-pulley *e* is keyed or otherwise properly secured, 45 which pulley is adapted to receive a belt or band driven by any suitable prime motor, thereby communicating motion to the movable parts of the machine. To the end of shaft *d* opposite that at which the driving-pulley *e* 50 is affixed thereto is secured a roller, *f*, having a rounded groove or groove of convex shape formed in its face or periphery, which groove

is transversely ribbed or fluted in its center, as shown in Figs. 1 and 6, and for a purpose to be presently explained.

g represents a strip of metal suitably secured to the side of arm *c* at its forward end, to the end of which strip is removably attached a guide, *h*, consisting of a piece of metal curved rearwardly toward a point underneath 55 roller *f*, and having a square groove, *i*, formed in its under face, the lower sides or faces of the walls of which groove are rounded or flare outwardly and downwardly, as seen in Fig. 1.

Extending outward from post *b* between the 60 bed *a* and arm *c* is another arm, *j*; the forward end of which is fitted to guide and support a vertical bar, *k*, the upper end of which is forked, and the upper ends of the arms of the fork are adapted to support the axle or journals of a 65 roller, *l*, having a convex periphery conforming substantially to the convex groove formed in the periphery of the roller *f*. Said roller *l* is supported directly under roller *f*, and so that the rounded face of the former will extend into the groove formed in the face of the 70 latter.

Bar *k* has a screw-threaded hole formed in its lower end, into which the screw-threaded stem *m* of the foot *n* is fitted. The foot *n* rests 75 upon a step, *o*, of rubber or similar material, secured to the bed *a*, and said foot has its outer surface or periphery preferably roughened, so that bar *k*, carrying roller *l*, can be adjusted vertically to a limited extent by the 80 turning of said foot, as will be readily understood.

A bar or strip, *p*, secured by screws or in any other suitable manner to the forward end 85 of arm *j*, is provided on its upper end with a 90 guide, *q*, consisting of an inverted-V-shaped piece of any suitable length, having the forward end of its upper edge extending into the square groove *i* of guide *h*, as clearly shown in Fig. 3.

The operation of our invention may now be explained and readily understood. The parts seamed together, as represented in Fig. 5, are placed astride the guide *q*, (which, in addition to operating as a guide, serves as a bed or support for the material,) so that the projecting portions *s* of the seam will enter groove *i* in guide *h*, and be thereby maintained in vertical position as it is drawn between rollers *f*, *l*, 95 100

by which it is smoothly pressed down or flattened without being spread, and undue strain thereby brought upon the stitches of the seam. The guides *h i q* not only direct the seam with exactness to the proper point between the rollers *f l*, but maintain the parts of the seam *s* in such positions that each will be rolled or pressed down with certainty in its own seat, as shown in Fig. 6, and all liability of one part *o* of the seam being pressed upon the other or the two parts being unduly spread apart is avoided.

The ribbed or fluted character of the face of the groove in roller *f* serves to draw or feed the seam through between the rollers with certainty, and the rubber step *o* operates to compensate at a uniform degree of tension for any unevenness in the thickness or bulk of the material comprising the seam.

The degree of pressure on the seam can be regulated to a nicety by means of the screw-threaded connection of the foot *n* with the bar *k*, which supports the lower presser-roller, *l*. By this means the distance between the two presser-rolls is regulated for seams of varying bulk, resulting from the use of material of different thicknesses.

Guide *h* is made removable to render it interchangeable with others, each having a groove, *i*, of different size or width, thus permitting the machine to be equipped with a guide, *h*, having a groove, *i*, suitable to the size or bulk of the seam to be pressed.

We claim—

1. A seam-pressing machine provided with two rollers arranged with their peripheries opposite to each other, supports for said rollers, mechanism consisting of a foot provided with a screw-threaded shank having a screw-threaded connection with the support of one of the rollers for adjusting the support of the latter roller to bring its periphery nearer to or remove it farther from the periphery of the

other roller, a step of rubber or analogous material for said foot to rest upon, guides for conducting the material to be pressed in proper position between said rollers, and mechanism, substantially as described, for rotating one of said rollers, all arranged and operating as and for the purposes hereinbefore set forth. 45

2. A seam-pressing machine provided with two rollers arranged with their peripheries or faces opposite to each other, mechanism, substantially as described, for rotating one of said rollers, and guides *h* and *q*, for conducting the material to be pressed in proper position between the rollers, guide *h* being provided on its face with the single square groove *i*, and guide *q* being in form substantially that of an inverted *V*, as and for the purposes herein- 50 before set forth.

3. The combination, with roller *l*, of bar *k*, having a screw-threaded hole formed in its lower end, foot *n*, having a screw-threaded stem, *m*, adapted to be screwed into the screw-threaded hole of the bar, and step *o*, of rubber or analogous material, for the foot to rest upon, whereby the position of said roller may be adjusted vertically and the yielding pressure of the step rendered regular, substantially 65 as and for the purposes hereinbefore set forth.

4. The combination of the guides *h* and *q* and their supports, the former guide being provided on its face with the square groove *i*, and the latter guide being of an inverted-*V* 70 shape, as set forth.

In testimony whereof we have signed our names to this specification, in the presence of two subscribing witnesses, this 8th day of June, 1886.

CHARLES W. HASELTON.
GRANVILLE P. FELT.
